LOCOMOTIVE STRUCTURE

William L. Lentz, Tuckahoe, N. Y., and Carl F. Kantola, Ashtabula, Ohio, assignors to The New York Central Railroad Company, a corporation of New York

Application September 26, 1935, Serial No. 42,344

13 Claims. (Cl. 105—2)

This invention relates to smoke lifting means for locomotives, and particularly steam locomotives of streamline type.

In a prior application for patent executed August 23, 1935, Serial No. 42,342, filed September 26, 1935, there is disclosed a streamline construction for locomotives including a cowling and hood about the body and forward portions of the boiler. This cowling is provided with an air scoop channel or chute opening at its forward end through its front or through the top of the hood and extending rearwardly about and beyond a streamlined smoke stack and terminating at its rear end adjacent to the stack in a deflector or scoop plate, the construction being such that in the forward travel of the locomotive air flowing rearwardly through the air scoop channel or chute and striking the deflector or scoop plate is deflected upwardly and rearwardly, whereby the smoke and gases issuing from the stack are carried upwardly to a predetermined height and caused to travel rearwardly above the horizontal plane of the top of the locomotive cab, thus preventing the smoke from the stack from striking the front of the cab and clouding the vision of the engineer and also preventing other well known nuisances occurring in the operation of a steam locomotive not so equipped. In such prior application is also shown the use of side scoops or chutes independent of the cowl scoop or chute for projecting streams of air upwardly and rearwardly into the free atmosphere to augment the smoke lifting action of the lifting streams produced by the cowl scoop. These side scoops or chutes, as shown in said prior application, are associated with and formed as parts of stairways or ladders leading to the front running board, the upper steps of the ladders being of perforate type and serving as gratings for the escape of the air streams.

The object of the present invention is to provide an improved construction of the side scoops or chutes wherein the air currents collected by said scoops, instead of being discharged at the sides of the locomotive into the free atmosphere, are entrapped and conducted through confined courses, as through ducts, to and discharged with force directly into the cowl scoop so as to strike the deflector or scoop plate and to be deflected upwardly thereby with the current of air from the cowl scoop, so as to augment the volume and increase the velocity of the smoke lifting current of air as well as to further increase the efficiency of the exhaust and ensure the lifting of the smoke and gases to the predetermined high dissipa-

tion level at any and all train haul speeds of the locomotive.

The invention consists of the features of construction, combination and arrangement of parts, hereinafter fully described and claimed, reference being had to the accompanying drawings, in which:—

Fig. 1 is a view in side elevation of a streamlined locomotive embodying the invention.

Fig. 2 is a front perspective view thereof. 10

Fig. 3 is a top plan view, on an enlarged scale, of the forward portion of the locomotive, with parts appearing in section, showing the smoke stack, cowl scoop and the auxiliary scoops co-operating therewith. 15

Fig. 4 is a side elevation, partly in section, of the parts appearing in Fig. 3.

Fig. 5 is a transverse section taken on line 5—5 of Fig. 4.

Referring now more particularly to the drawings, 1 designates a steam locomotive having a boiler 2, cab 3, side running boards 4, and suitably streamlined smoke stack 5 and auxiliary steam exhaust 6. Enclosing the boiler 2 longitudinally between the front of the cab and tip of the pilot is a sheet steel streamline cover comprising a cowling 7 and a hood 8. The cowling 7 extends transversely over the boiler in spaced relation thereto between the running boards and is supported by a suitable framework structure secured to the boiler shell and to the running boards. The hood 8 extends vertically at an upward and rearward slope from the tip of the pilot to the forward end of the firebox portion of the boiler, where it is joined to the front of the cowling, and said hood is parabolically curved transversely to deflect head or angle wind currents toward the sides of the locomotive. The construction of these parts and their operating characteristics may accord with the disclosure in these respects set forth in the aforesaid prior application. 40

The smoke stack and auxiliary steam exhaust are of streamline contour or provided with a suitable streamline fairing or jacket 9, and these elements are arranged in a depressed portion at the forward end of the cowling. This depressed portion is formed by vertical longitudinal walls 10 and an upwardly and rearwardly inclined rear end wall 11, forming an air channel or chute 12 extending from the front of the cowling about and on opposite sides of the smoke stack to a point adjacent to and in rear thereof and terminating at its rear end in the wall 11. This chute communicates at its forward end with an inlet opening 13 formed in the central portion of the top 50

of the hood, which opening may be covered by a grille or screen 14 connecting the side walls of the opening and preserving the contour of such portion of the hood. The wall 11 slopes at a proper angle to form a scoop plate or deflector to deflect currents of air upwardly and rearwardly. In the forward travel of the locomotive air entering the chute through the inlet opening 13 travels rearwardly therein on opposite sides of and beyond the smoke stack and auxiliary steam exhaust and strikes against the scoop 11, whereby this air and the streams of air flowing along the sides of the smoke stack are shot upwardly and rearwardly to a level above the top of the locomotive cab, carrying with them the smoke and gases issuing from the smoke stack. The top of the forward portion of the channel or chute and the divisions of this channel on opposite sides of the smoke stack may be left open, or may be closed by a cover plate between the hood and a point coinciding with the transverse center of the smoke stack, if desired.

The present invention provides means for producing and projecting auxiliary currents or blasts of air into the channel or chute to mingle with and augment the volume and increase the smoke lifting effect of the main blast or current of air on the smoke and gases issuing from the smoke stack. To this end the locomotive is provided at each side and at the front thereof with a stairway or ladder structure 15 leading upward to the forward end of the running board 4 at that side. Each ladder structure comprises outer and inner side rails or sheets 16 and 17, steps 18 extending transversely therebetween, and a back wall 19 spaced from the rear edges of all the steps except the bottom and top steps and forming an enclosure which is open at front, closed at bottom and top by the bottom and top steps and at the rear by the wall 19. The ladder slopes in an upward and rearward direction and the wall 19 correspondingly slopes and forms an inclined wind scoop, each ladder thus being constructed to serve the function of a wind chute. Air in the forward travel of the locomotive enters this chute through its open front and through the spaces between the steps and upon striking the deflector plate or wall 19 shoots upwardly through the passage between said plate or wall and the intermediate steps.

At their upper ends the chute passages communicate through ports 20 formed in the sides of the cowling 7 with the lower ends of ducts 21 disposed between the cowling and adjacent sides of the boiler shell 2. These ducts extend upwardly and rearwardly at the sides of the boiler and over the top of the boiler beneath the cowling and communicate at their upper or delivery ends with opposite sides of the rear end of the channel or chute 12 through series of lateral ports or nozzle openings 22 formed in the side walls of said channel, said ports or nozzle openings being provided with louvres or deflector plates 23 for guiding the streams of air issuing therefrom with velocity from the ducts 21. Air entering each duct from its associated ladder scoop thus discharges through the nozzles 22 in the form of blasts of high intensity which mingle with the current of air traversing the channel 12 and striking the scoop plate 11. The air current supplied by the channel 12 is thereby augmented in volume and intensity by the auxiliary currents or air blasts from the ducts 21, resulting in the production of a lifting stream of air of large volume and of a sufficient force to ascend to a considerable

height, ensuring the lifting of the smoke and gases issuing from the smoke stack to the intended high dissipation level at all locomotive train haul speeds and when the locomotive is traveling at comparatively slow speed. This lifting action of the air blasts also promotes the efficiency of the draft through the smoke stack, as will be readily understood. The rear ends of the ducts 21 may, as shown, be connected in rear of the scoop plate 11 by a cross duct 24, and the top walls of the ducts 21 and 24 may be provided with vent apertures or slots 25 to allow any air in excess of that which may freely pass through the nozzles 22 to escape to the free atmosphere, thus preventing any possible choking of the air within the ducts. By thus providing the ducts 21 to supply additional currents of air and confining the air until it discharges into the channel 12 the production of a smoke lifting current of large volume and high velocity is ensured to effect the lifting of the smoke to the intended level not only at different locomotive speeds but under all contrary natural wind conditions to prevent the smoke nuisances to which the engineer in the cab and passengers in the cars of the train are ordinarily subjected.

While the structural organization shown for the purpose set forth is preferred, it will, of course, be understood that the same is merely exemplificative, and that changes in the form, proportions and arrangement of the parts may be made within the scope of the appended claims without departing from the spirit or sacrificing any of the advantages of the invention.

What is claimed is:—

1. A locomotive having a cab, a smoke stack located forwardly of the cab, an air scoop adjacent said stack and at least partially surrounding the stack and having an inclined surface for directing the scooped air upwardly to lift the smoke issuing from the stack to a level above the level of the cab, air scoops at the front and on opposite sides of the locomotive and having inclined surfaces for directing air upwardly and rearwardly, and air conductors leading from the second-named scoops to and communicating with the first-named scoop.

2. A locomotive having a boiler, a cab, a smoke stack located forwardly of the cab, a streamline cowling over the top and sides of the boiler, an air scoop adjacent the stack and at least partially surrounding the stack and partly enclosed by the cowling for producing a current of air and including a surface for directing the scooped air upwardly to lift the smoke issuing from the stack to a level above the level of the cab, air scoops at the sides of the locomotive, and air conductors leading from the second-named scoops beneath the cowling to and communicating with the first-named scoop.

3. A locomotive having a cab, a smoke stack located forwardly of the cab, an air scoop adjacent to and at least partially surrounding said stack and including an inclined surface to lift the smoke issuing from the stack to a level above the level of the cab, running boards at the sides of the locomotive, air scoops at the front of the locomotive leading to points adjacent the running boards, and air conductors leading from the second-named scoops to and communicating with the first-named scoop.

4. A locomotive having a boiler, a cab, a smoke stack located forwardly of the cab, a streamline cowling over the top and sides of the boiler, an air scoop adjacent the stack and at least partially

surrounding the stack and partly enclosed by the cowling for producing a current of air and including a surface for directing the scooped air upwardly to lift the smoke issuing from the stack to a level above the level of the cab, running boards at the sides of the locomotive, inclined air scoops at the front of the locomotive leading upwardly to points adjacent the forward ends of the running boards, and air conductors leading from the second-named scoops beneath the cowling to and communicating with the first-named scoop.

5. A locomotive having a boiler, a cab, a smoke stack located forwardly of the cab, a cowling over the top of the boiler having a portion structurally formed adjacent the stack to provide an air scoop at least partially surrounding and including an inclined surface to lift the smoke issuing from the stack to a level above the level of the cab, air 10 scoops at the sides of the locomotive, and air conductors leading from the second-named scoops to and communicating with opposite sides of the first-named scoop at the rear thereof.

6. A locomotive having a boiler, a cab, a smoke stack located forwardly of the cab, a cowling over the top and sides of the boiler having a portion structurally formed adjacent the stack and at least partially surrounding the stack to provide an air scoop for producing a current of air 15 and including a surface for directing the scooped air upwardly to lift the smoke issuing from the stack to a level above the level of the cab, air scoops at the front of the locomotive and on opposite sides thereof, and air conductors leading from the second-named scoops beneath the cowling to and communicating with the first-named scoop at opposite sides thereof.

7. A locomotive having a boiler, a cab, a smoke stack located forwardly of the cab, a cowling over the top of the boiler having a portion structurally formed adjacent the stack to provide an air scoop at least partially surrounding the stack for producing a current of air and including a surface for directing the scooped air upwardly to lift the smoke issuing from the stack to a level above the level of the cab, running boards at the sides of the locomotive, air conductors at the front of the locomotive in advance of and leading upwardly to points above the level of the running boards, 20 and air conductors leading from the first-named conductors beneath the cowling to and communicating with the first-named scoop.

8. A locomotive having a boiler, a cab, a smoke stack located forwardly of the cab, a cowling over the top and sides of the boiler having a portion structurally formed adjacent the stack to provide an air scoop at least partially surrounding the stack for producing a current of air and including a surface for directing the scooped air upwardly 25 to lift the smoke issuing from the stack to a level above the level of the cab, running boards at the sides of the locomotive, air scoops at the front of the locomotive in advance of and leading upwardly to points above the level of the running boards, and air conductors leading from the second-named scoops beneath the cowling to and communicating with opposite sides of the first-named scoop at the rear thereof.

9. A locomotive having a boiler, a cab, a smoke 30 stack located forwardly of the cab, a cowling over

the top of the boiler provided with a depressed portion forming an air scoop channel at least partially surrounding said stack and provided with a deflector for deflecting air from the channel upwardly to lift smoke issuing from the stack to a level above the level of the cab, air scoops at the sides of the locomotive, and conductors leading from said scoops to and communicating with said channel.

10. A locomotive having a boiler, a cab, a smoke 35 stack located forwardly of the cab, a cowling over the top and sides of the boiler provided with a depressed portion forming an air scoop channel at least partially surrounding the stack and provided with a deflector for deflecting air from the channel upwardly to lift smoke issuing from the stack to a level above the level of the cab, air 40 scoops at the sides of the locomotive, and conductors leading from said scoops beneath the cowling to and communicating with said channel.

11. A locomotive having a boiler, a cab, a smoke stack located forwardly of the cab, an air scoop located adjacent to and at least partially surrounding said stack for producing a current of air to lift the smoke issuing from the stack to a 45 level above the level of the cab, running boards at the sides of the locomotive, air guiding surfaces at the sides of the locomotive leading from the forward portion of the locomotive at an upward and rearward angle of inclination to the level of the running boards and acting as air scoops to pick up air upon forward movement of the locomotive, spaced ladder tread steps subdividing the entrance to each side air scoop, and air conductors leading from the side air scoops to the first-named scoop.

12. A locomotive having a boiler, a cab, a smoke stack located forwardly of the cab, a cowling over the top and sides of the boiler provided with a depressed portion forming an air scoop channel 50 at least partially surrounding the stack and provided with a deflector for deflecting air from the channel upwardly to lift smoke issuing from the stack to a level above the level of the cab, running boards at the sides of the locomotive, air scoops 55 at the sides of the locomotive leading upwardly to the running boards and including spaced ladder tread steps subdividing the entrances of the scoops, and conductors leading from said scoops beneath the cowling and communicating with said channel.

13. A locomotive having a boiler, a cab, a smoke stack located forwardly of the cab, a cowling over the top and sides of the boiler provided with a depressed portion forming an air scoop channel 60 at least partially surrounding the stack terminating in rear thereof in a deflector for deflecting air from the channel upwardly to lift smoke issuing from the stack to a level above the level of the cab, running boards along the sides of the locomotive, air scoops at the sides of the locomotive below and in advance of and leading upwardly toward the running boards, spaced ladder tread steps subdividing the entrances of said scoops, and conductors leading from said scoops beneath the cowling at opposite sides of the locomotive and communicating with the side of the scoop adjacent to said deflector.
